UNITED STATES PATENT OFFICE.

EDWARD A. CUNNIF, OF WALTHAM, MASSACHUSETTS, ASSIGNOR TO DRAPER CORPORATION, OF HOPEDALE, MASSACHUSETTS, A CORPORATION OF MAINE.

FILLING-CUTTING MECHANISM FOR SHIFTING-SHUTTLE BOX LOOMS.

Application filed August 21, 1924. Serial No. 733,256.

To all whom it may concern:

Be it known that I, EDWARD A. CUNNIF, a citizen of the United States, and resident of Waltham, county of Middlesex, State of Massachusetts, have invented an Improvement in Filling-Cutting Mechanism for Shifting-Shuttle-Box Looms, of which the following description, in connection with the accompanying drawing, is a specification, 10 like characters on the drawing representing like parts.

This invention is particularly designed for removing projecting filling ends from the selvage of cloth woven in a shifting shuttle box or drop box loom, especially when cross-bar fabrics are woven. When in the weaving of such fabrics the stripes or crossbars woven by one of the shuttles are widely separated, a long loop of filling is left extending from one bar to the next succeeding bar upon the reparticipation of the shuttle in the weaving operation. These loops of filling must be removed from the selvage to make the fabric salable and it is difficult, if not impossible, to remove them by the usual singeing operations and laborious and expensive to remove them by hand.

The present invention provides means acting automatically during the weaving operation by which such loops are first cut or severed and then the ends are cut off close to the selvage.

The present invention also provides means acting automatically during the operation of the loom to remove in a novel and efficient manner any filling ends left projecting at the selvage.

These and other objects and features of the invention will appear more fully from the accompanying description and drawings and will be particularly pointed out in the claims.

Since the invention relates to the mechanism for removing the filling loops or ends at the selvage and is not concerned with any particular construction of loom and since the construction and operation of the loom, including the drop box loom, is well-known and familiar to those skilled in the art, it is only necessary to illustrate and describe herein those parts of the loom directly concerned with a preferred embodiment of the invention.

In the drawings:

Fig. 1 is a view in vertical cross-section taken through the lay and breast-beam of a two box shifting shuttle box loom adjacent the temple and showing a preferred form of the invention, certain of the parts being broken away.

Fig. 2 is a plan view of the construction shown in Fig. 1 forward of the lay and illustrating the cloth being woven.

Figs. 3, 4, and 5 are perspective views showing successive steps in the weaving of 65 the cloth and the cutting of a loop.

While the invention in certain of its aspects may be employed in removing filling ends from the selvage of cloth being woven in various types of looms it is, as already 70 pointed out, particularly designed for use in connection with a drop box loom weaving comparatively widely separated stripes or bars of filling.

A lay sword 1 is shown supporting the 75 usual lay 2, hand rail 3, and reed 4. The running shuttle 5 is shown in position on the lay and the position of the other shuttle 6 of a two box loom is indicated in dotted lines in Fig. 1. The shuttle 6 is shown in 80 its inactive position. Upon the next shift of the shuttle boxes the shuttle 6 will take the position on the lay while the shuttle 5 will be correspondingly elevated to its inactive position.

The breast-beam 7 carries rigidly supported thereon in the usual manner, the temple stand 8. In the temple stand is mounted for reciprocating movement the shank 9 of an ordinary type of temple. The temple 90 head comprises the usual pod 10 and cap 11 extending transversely of the shank and enclosing the usual temple rolls 12 which act to maintain the cloth at the required width.

The construction is the same at both sides 95 of the loom and it is therefore sufficient to illustrate and describe the construction at one side. The temple is normally and yieldingly projected rearward by the usual spring, not shown, in the temple stand and is moved 100 slightly forward at each beat up of the lay by the engagement of the lay with the heel 13 depending from the temple head.

The cloth 14 being woven passes from the 105 shed through the temple head over the temple rolls and thence over the breast-beam

and is taken up by the usual take up roll, not shown.

In Figs. 3, 4, and 5 is illustrated a piece of cloth in which narrow crossbars or stripes 15 are formed by the filling from one shuttle alternating with comparatively wide sections 17 woven by filling from the other shuttle. It will be seen that a long loop, shown in the dotted line 18, will normally be left at the selvage connecting the stripes or crossbars 15. Such loops, as already pointed out, have heretofore required expensive and laborious operations for their removal and are too long to be removed by the usual singeing operation without injury to the cloth.

In the preferred embodiment of the present invention there are two main elements; first a cutter knife by which these loops are cut into two parts and second, a cutting mechanism subsequently acting to shear or cut off the two ends close to the selvage.

The cutter knife comprises a small blade 19 having a sharp rear edge and mounted to extend transversely of the plane of the cloth adjacent the selvage and forward of the fell. This position is conveniently secured by mounting the blade 19 in a slotted horizontally extending shank 20 adjustably secured by means of the set screw 21 to the top of the temple cap 11.

It will thus be seen, as shown in Fig. 3, that the last pick of filling 22 in the last stripe 15 woven will be carried by its shuttle forward of the blade 19 and will be held by the shuttle in its inactive position. During the weaving of the intervening section 17 by the other shuttle the cloth will be gradually taken up and the filling 22 be carried forwardly and beneath the blade 19. The first pick 23 taken by the shuttle in reparticipating in the weaving to form the next stripe 15 will pass to the rear of the blade 19 as shown in Fig. 4. There will thus be formed a loop which will be drawn about the blade 19 as shown in Fig. 5 and finally as the cloth is further taken up this loop drawn forwardly against the cutting edge of the blade 19 will be severed, leaving the depending ends such as 24 and 25.

The cutting mechanism for removing the ends at the selvage, whether ends such as 24 and 25 or any others left projecting, has its field of action adjacent the selvage forward of the cutter knife and acts to cut off, close to the selvage, these ends.

This cutting mechanism is preferably supported from the breast-beam and operated by a bunter carried by the lay.

In the preferred construction illustrated, the bracket 26 is bolted at 27 to the rear face of the breast-beam 7 and presents a rearwardly projecting arm 28 at an acute angle to the selvage. On this arm is mounted a stand 29 slotted longitudinally at 30. In

the rear end of the slot is mounted a fixed vertical cutter blade 31 and parallel therewith a vertical guide 32. A hook shaped cutter blade 33 is mounted to slide and rock in the slot 30 and co-operates at its hooked end with the blade 31. A plate 34 secured to the stand 29 and overhanging the slot 30 limits the upward movement of the cutter blade 33. The cutter blade 33 is provided at its forward end with an upstanding arm 35. This arm is in the path of a bunter 36 bolted at 37 to the hand rail 3. A spring 38 engaging a lug 39 on the arm 35 and a lug 40 on the stand 29 acts normally to project the movable cutter blade rearwardly while the bunter 36 acts upon each beat up of the lay to slide and rock the movable cutter blade forwardly and cause it to have a co-operating shearing action with the fixed cutter blade 31.

This cutting mechanism is so mounted and positioned that the movable cutter blade is located immediately adjacent the path of the selvage and its rearward end extends, when in open position, beneath the selvage so that the closing and cutting movement takes place in a direction upwardly and outwardly from the selvage. Thus any filling ends depending at the selvage are caught and sheared off by the cutting mechanism.

To prevent any filling ends from being thrown upwardly a guide arm 41 is mounted on the stand 29 close to the plate 32 and extends above or overhangs the plane of the cloth. This arm thus acts to restore to the cutting field of the cutting mechanism any ends thrown upwardly.

The position of the cutting mechanism by which the plane of movement of the movable cutter blade is normal to the plane of the cloth at an acute angle to the selvage insures in an effective manner the filling ends being caught and severed.

The position of this mechanism is further determined by adjusting it bodily transversely until the selvage guides against the fixed cutter blade 31 as shown in Fig. 2.

There is thus presented simple and efficient means readily attachable to the existing looms by which the desired results are secured.

Having thus described the invention, what is claimed as new, and desired to be secured by Letters Patent, is:

1. Mechanism for removing long filling loops from the selvage of cloth being woven in a shifting shuttle box loom having a temple comprising a cutter knife carried by the temple and extending transversely of the plane of the cloth adjacent the selvage and between the fell and the rear of the temple with its cutting edge facing rearwardly whereby the loop of filling at the selvage formed by a shuttle upon its reparticipation

in weaving is drawn forwardly around the knife and severed as the cloth is taken up in the weaving operation, and cutting mechanism having its field of action adjacent the 5 selavage forward of said cutter knife and acting to cut off close to the selavage the projecting ends of the loop left after severance by the cutter knife.

2. A shifting shuttle box loom comprising 10 a cutter knife mounted on the loom to extend transversely of the plane of the cloth adjacent the selavage forward of the fell and with its cutting edge facing rearwardly whereby the loop of filling formed at the 15 selavage by a shuttle upon its reparticipation in weaving is drawn forwardly around the knife and severed as the cloth is taken up in the weaving operation.

3. Filling and cutting mechanism for a 20 loom comprising a fixed vertical cutter blade located immediately adjacent the path of the

selavage, a hook shaped movable co-operating cutter blade extending when in open position beneath the selavage and having its closing and cutting movement in a direction upwardly and outwardly, the plane of movement of said movable blade being normal to the plane of the cloth and at an acute angle to the selavage, and means for intermittently effecting the opening and closing 25 movement of the movable cutter blade, whereby the filling ends projecting from the selavage are severed close to the selavage.

4. Filling cutting mechanism comprising 30 the construction defined in claim 3 together with a guide arm associated with the fixed blade and overhanging the plane of the cloth and acting to restore to the cutting field any ends thrown upwardly.

In testimony whereof, I have signed my 40 name to this specification.

EDWARD A. CUNNIFF.
